UNITED STATES PATENT OFFICE.

JAY HUGHES, OF ATKINSON, NEBRASKA.

ROAD-SCRAPER.

1,245,107.

Specification of Letters Patent. Patented Oct. 30, 1917.

Application filed May 18, 1917. Serial No. 169,511.

To all whom it may concern:

Be it known that I, JAY HUGHES, a citizen of the United States, residing at Atkinson, in the county of Holt and State of Nebraska, have invented certain new and useful Improvements in Road-Scrapers; and I do hereby declare the following to be a full, clear, and exact description of the invention, such as will enable others skilled in the art to which it appertains to make and use the same.

This invention relates to improvements in a road scraper and has for one of its objects the provision of a device of this character, which is especially adapted for removing the dirt from the sides of a road and depositing the same in the center thereof, which gives the correct grading to each side thereof.

Another object of this invention is the provision of a pair of frames arranged in parallelism with each other so that the scraping means carried thereby will carry and deposit the dirt from the sides of the road on to the center thereof.

A further object of this invention is to provide means for permitting the frames to be moved toward and from each other as desired, so as to regulate the point of the sides of the road that the dirt is to be removed from.

A further object of this invention is the provision of diagonally arranged scraper blades on each of the frames for cutting and carrying the dirt from the sides of the road to the center thereof.

A further object of this invention is the provision of means for raising and lowering the frames for engaging and disengaging the scraper blades with the ground and also regulating the depth of the cutting action of said blades.

A further object of this invention is the provision of a plurality of diagonally arranged colters positioned forwardly of the scraper blades for cutting the ground and trash that may accumulate under the frames.

A still further object of this invention is the provision of means for raising and lowering the colters with relation to the frames, whereby the cutting action thereof may be regulated.

A further object of this invention is to provide cushioning means between the frames, which will absorb shocks to the

frames and aid in preventing them from moving out of parallelism with each other.

A still further object of this invention is the provision of a road scraper of the above stated character, which shall be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:

Figure 1 is a top plan view of a road scraper constructed in accordance with my invention.

Fig. 2 is a longitudinal sectional view of the same.

Fig. 3 is a front elevation of the same,

Fig. 4 is a rear elevation of the road scraper,

Fig. 5 is a fragmentary transverse sectional view illustrating the means for raising and lowering the colters,

Fig. 6 is a fragmentary plan view illustrating the arrangement of the colters,

Fig. 7 is a longitudinal sectional view of the cushioning means,

Fig. 8 is a transverse sectional view of the same,

Fig. 9 is a fragmentary sectional view of one of the means for raising and lowering the frames,

Fig. 10 is a fragmentary vertical sectional view of the means for adjusting the colters and furnishing the journals thereof with lubricant,

Fig. 11 is a detail view illustrating a pawl and ratchet mechanism employed for raising and lowering the frames,

Fig. 12 is a fragmentary side elevation illustrating the openings in one of the side members of the frame to permit the dirt to pass outwardly of the frame.

Referring to the drawings in detail, the numerals 1 and 2 indicate frames, which are arranged in parallelism with each other as clearly shown in Fig. 1. The frames 1 and 2 consist of inner and outer side members 3 and 4. The outer side members 4

BEST AVAILABLE COP

1,245,107

2

are arranged slightly in advance of the inner side members and are connected by diagonally arranged beams 5, 6 and 7 to which are secured at the lower edge thereof, 5 scraping blades 8. The scraping blades 8 that are carried by the beams 7 and 6 have their outer ends bent forwardly and secured to the outer side members 4 for preventing dirt and trash from catching in the scraper 10 blades while in operation. The inner side members have openings 9 arranged adjacent the inner ends thereof for the purpose of allowing the dirt cut or scraped by the blades to pass outwardly between the inner side 15 members 3 of the frames 1 and 2. Draft chains 10 are connected to the forward ends of the frames 1 and 2 so that the device may be readily connected to a draft power.

A plurality of diagonally arranged supporting members 11 are secured to the frames 1 and 2 and slidably mounted therein are pairs of hollow supporting rods 12, which have secured to their lower ends, journals 13. The journals 13 are slidably 20 supported in substantially U-shaped brackets 14 carried by the inner and outer side members 3 and 4 and the longitudinal bracing members 15, which are secured to the diagonally arranged beams 5 and 6. The 25 journals 13 have rotatably mounted therein, shafts 16 on which are mounted, a plurality of colters or cutting disks 17, the colters or cutting disks 17 being spaced apart by blocks 18. The shafts 16 are supported 30 diagonally of the frames and one in front of the other as clearly shown in Fig. 6. The hollow rods 12 are externally screwthreaded and have threaded thereon adjusting nuts 18', whereby the rods may be raised and 35 lowered for regulating the cutting action of the disks. Secured to the upper ends of the hollow rods 12 are grease cups 19 for the purpose of furnishing the journals 13 with lubricant. Coiled springs 20 are 40 mounted upon the rods 12 for normally urging the journals downwardly with relation to the frames 2 and 1, thus it will be seen that by threading the nuts 18' upon the rods 12 in a clockwise direction, the colters or 45 cutting disks 17 will be raised.

A plurality of transversely extending bracing strips 21 are carried by the side members 3 and 4 of the frames 1 and 2; the strip A constituting one of the strips 21 50 upon the frame 2 has journaled therein a rod 22 to which is secured a cable 23 that extends through the inner side members 3 of the frame 2 and is secured to the inner side members 3 of the frame 1. A similar side member 3 of the frame 1 has journaled 55 in one of the members 11 of the frame 2 and has connected thereto, a cable 25, which is secured to the inner side members 3 of the frame 1. Each of the rods 22 and 24 have secured thereto, handles 26 60 for rotating said rods to wind the cables 65 23 and 25 thereon for moving the frames 1 and 2 in the direction of each other. Each of the rods 22 and 24 have secured thereto, ratchet gears 27, which are engaged by spring actuated dogs 28 for preventing the rods 22 and 24 from rotating in a reverse direction, whereby the frames 1 and 2 may be adjusted in relation to each other and held in any desired adjusted position.

Secured to the corners of each of the frames 1 and 2 are supporting structures 30 constructed from angle iron members 31, which are secured to the frames 1 and 2 as shown at 32 and have secured in their upper ends, guide blocks 33. The 70 guide blocks 33 are apertured to slidably receive a rod 34, which extends through the frames 1 and 2 and have swiveled to their lower ends, rollers 35. Pairs of relatively spaced housings 36 are located with- 75 in the supporting structures 30 and have journaled therein, rollers 37. Positioned between the housings 36 and surrounding the rods 34 are coiled springs 38, which bear against blocks 39 carried by the rods. The 80 blocks 39 have connected thereto, cables 40, which extend through apertures in the tops of the housings 36 and pass about the rollers 37. The cables after passing about the rollers 37 are secured to rods 41, which are 85 journaled in the frames 1 and 2 and in reinforcing members 43. The rods 41 have connected thereto, handles 44 and also ratchet wheels 45, similar to the ratchet wheels 27, which are engaged by spring actuated dogs 90 46. By rotating the rods 41 by the handles 44 winding the cables 40 thereon, the cables draw the blocks 39 downwardly, moving the wheels 35 in engagement with the ground and elevating the frames 1 and 2, thus it will 95 be seen that any corners or the entire frames may be elevated when desired so as to engage and disengage the scraper blades 8 and cutters from engagement with the ground to render the device operative and inoperative when desired.

Pivotedly secured to the front ends of the outer side members 4 of the frames 1 and 2 are substantially U-shaped arms 47 to which are secured rods 48 on which are 100 journaled rollers 49. Extensions 50 are secured to the ends of the side members 4 of the frames 1 and 2 and overlie the arms 47, and have mounted therein, rods 51, which are secured to blocks 52 that are in turn 105 secured to the arms 47. Adjusting nuts 53 are threaded to the rods 51 for raising and lowering the arms 47 to engage and disengage the rollers 49 from engagement with the ground.

Coiled springs 54 are positioned upon the rods 51 between the extensions 50 of the arms 47 for normally urging said arms 110 downwardly. The rods 48 to which the rollers 49 are journaled are swivelly con- 115

120

125

130

nected to the arms 47 so that they may turn freely with relation to the frames during the operation of the device.

Connecting members 55 are removably secured adjacent each end of the inner side members 3 of the frames 1 and 2 and each are constructed from a pair of channel bars 56. The channel bars 56 are connected together by a plurality of relatively spaced rectangular blocks 57. The fastening elements 58 pass through apertures 59 in a pair of the blocks 57, for securing the connecting members 55 to the frames 1 and 2. The blocks that receive the fastening elements 58 have connected thereto, rods 60, which are slidably received within the adjacent block 57 and on which are mounted coiled springs 61 for the purpose of cushioningly supporting the block 57 that receives the fastening elements 58, whereby shock absorbing means is provided between the frames 1 and 2 and which construction will permit the frames 1 and 2 to be moved toward and from each other as desired.

25 In operation, a suitable draft power is connected to the chains 50 and the frames 1 and 2 are adjusted from each other to the desired point so as to make the device operable upon each side of the road and by 30 forward movement of the frames 1 and 2, the scrapers cut into the ground and carry the loose dirt to the center of the road. The cutters or colters 18 cut into the ground and loosen the same, making it easy for the 35 scrapers to deposit the loose dirt into the center of the road.

By rotating the rods 41 the rollers 35 may be moved into engagement with the ground for disengaging the cutters and scrapers 40 from the ground so that the device may be conveyed from one point to another in an inoperative state.

While I have shown and described the preferred embodiment of my invention, it 45 will be understood that minor changes in construction, combination and arrangement of parts may be made without departing from the spirit and scope of the invention as claimed.

50 Having thus described my invention, what I claim is:

1. A road scraper comprising a pair of frames, flexible means connecting said

frames, means connected to said flexible means for moving said frames toward and 55 from each other, shock absorbing means connecting said frame, and cutting means carried by said frames.

2. A road scraper comprising a pair of frames, means for connecting said frames, 60 cutting means carried by said frames, supporting structures carried by said frames, rods slidably mounted in said supporting structures, blocks carried by the rods and 65 slidably in the supporting structure, coiled springs interposed between said blocks and frames, cables connected to said blocks, rods journaled in said frames, a ratchet mechanism carried by said rods, said cables attached to said rods, and handles connected 70 to said rods for rotating said last named rods, and rollers journaled to the first named rods.

3. A road scraper comprising a pair of frames, means for connecting said frames, 75 scrapers carried by said frames, a plurality of rods carried by said frames, shafts journaled to said rods, colters journaled on said shafts, means for raising and lowering the rods to engage and disengage the colters 80 with the ground.

4. A road scraper comprising a pair of frames, means for connecting said frames, a plurality of hollow rods carried by said frames, journals carried by said rods, 85 screwthreads formed on said rods, shafts journaled in the journals, colters journaled on said shafts, adjusting nuts on said rods for raising and lowering said rods, and grease cups carried by said rods for furnishing the journals with lubricant.

5. A road scraper comprising a pair of frames, cutting means carried by said frames, members connecting said frames, blocks slidably mounted in said frames, 95 cushioning means engaging said blocks, means for connecting the blocks to the frames to form a shock absorber between said frames.

In testimony whereof I affix my signature 100 in presence of two witnesses.

JAY HUGHES.
